UNITED STATES PATENT OFFICE.

JOHN R. FOSTER, OF ARLINGTON, MASSACHUSETTS.

DESIGN FOR A STAND FOR DISPLAYING PICTURES OR OTHER ARTICLES.

45,000.

Specification for Design.

Patented Dec. 9, 1913.

Application filed September 2, 1913. Serial No. 787,811. Term of patent 3½ years.

To all whom it may concern:

Be it known that I, JOHN R. FOSTER, a citizen of the United States, residing at Arlington, in the county of Middlesex and Commonwealth of Massachusetts, have invented a new, original, and ornamental Design for a Stand for Displaying Pictures or other Articles, of which the following is a specification, reference being had to the accompanying drawing, forming a part thereof.

The figure in the drawing is a perspective view of a stand for the display of small pic-

tures, mirrors, picture frames, plaques and similar articles.

I claim:

The ornamental design for a stand for displaying pictures, or other articles, as shown.

In testimony whereof, I have signed my name to this specification, in the presence of two subscribing witnesses.

JOHN R. FOSTER.
